US0D1037463S

(12) **United States Design Patent** (10) **Patent No.:** **US D1,037,463 S**
(45) **Date of Patent:** **** Jul. 30, 2024**

(54) **HEALTH MONITOR AND STRAP**

(71) Applicant: **CURRENT HEALTH LIMITED**,
Edinburgh (GB)

(72) Inventors: **Danielle Armstrong**, Edinburgh (GB);
Iain Macdonald Taylor, Edinburgh (GB);
Stephen John Johnston,
Edinburgh (GB)

(73) Assignee: **CURRENT HEALTH LIMITED**,
Edinburgh (GB)

(**) Term: **15 Years**

(21) Appl. No.: **29/918,067**

(22) Filed: **Nov. 24, 2023**

(57) **CLAIM**

The ornamental design for a health monitor and strap, as shown and described.

DESCRIPTION

FIG. 1 is a front perspective view of a health monitor and strap from above and left side;

FIG. 2 is a rear perspective view from above and right side;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate environment and form no part of the claimed design.

1 Claim, 8 Drawing Sheets
